Chicago, Ill.

Continuation of application Serial No. 494,743,
November 10, 1930. This application August 2,
1933. Serial No. 683,283

3 Claims. (Cl. 94—4)

My invention relates to the construction of retaining curbs such as is commonly necessary to retain certain road surfacing materials now in common use such as bricks, blocks, asphaltic and bituminous compositions.

A particular object of my invention is to provide a method and means of resurfacing old roads where the wearing surface of such road has been rough and where a resurfacing of such road is necessary to salvage the original road structure, and my invention is particularly well adapted for the resurfacing of old concrete roads which have begun to crack up or disintegrate from various causes.

A further purpose of my invention is to provide an economical, simple and practical means of substantially holding resurfacing materials when they are laid onto a concrete slab for resurfacing purposes.

I attain the objects of my invention by the device described in the annexed specification, recited in the claims and illustrated in the accompanying drawing in which like reference numerals indicate like parts in the several figures, the same being a continuation of application Serial No. 494,743, filed Nov. 10, 1930.

Referring to the drawing:

Figure 1 is a cross section of a pavement slab in a condition of failure, showing a reinforcing construction therefor and disclosing straight, rectangular retaining curb members for the retention of the resurfacing materials thereon, and in this case illustrating brick as the resurfacing material;

Fig. 2 is a cross section of a road slab in a condition of failure together with a cross section of brick resurfacing placed thereon and retained by an angle plate with outwardly projected flanges therefor;

Fig. 3 is a cross section of a road slab construction in a condition of failure and showing a resurfacing thereof with brick and disclosing along the sides a retaining curb of corrugated metal strips;

Fig. 4 is a cross section of a road construction where the base has been disintegrating and where the surface has been covered by a layer of asphalt supported along the sides by retaining curbs in the form of a channel bar;

Fig. 5 is a cross section of a road construction showing signs of disintegration and resurfaced by brick or other suitable blocks and showing in connection therewith retaining curb plates substantially held in place by tie rods holding engaging brackets supporting the retaining curb

plates and pressing against the outside edge of the old slab;

Fig. 6 is a cross section of road slab resurfaced with brick after the slab has worn and showing a modified form of curb plate;

Fig. 7 is a detail of a portion of a road slab disclosing a detail of an angle plate with the angle turned in and held in place by a tie rod;

Fig. 8 is a perspective disclosing the manner of engaging the retaining curb plates by the tie rods either by bolt and nut holding means or by providing lock notches on the ends of the tie rods and showing an expansive connection between the adjacent aligned retaining curb members of my invention; and

Fig. 9 is a perspective of a detail showing an expansive connection between adjacent ends of aligned retaining curb plate members.

Referring in detail to the construction of my invention and the preferred manner of using the same I provide a novel and practical retaining curb plate for substantial aid in resurfacing road structures that have had certain failures resulting from unusual strains and resulting in a partial disintegration of the surface of the old road structure.

In resurfacing the old road structures with brick or asphalt or other substantial and suitable materials it has been the common practice to build up along the sides a concrete shoulder for retaining the resurfacing materials and designed in a manner that is excessively expensive both in material used and labor required to lay it.

In recent years many miles of concrete slab pavements have been built and in connection with its normal use it has been clearly demonstrated that due to its inability to withstand exposure to the elements, expansion and contraction under temperature changes, and the freezing of absorbed moisture, etc., such concrete slabs are beginning to crack and disintegrate to an alarming extent and unless resurfaced with some suitable wearing surface they will soon become total failures and total losses.

In this connection the above mentioned concrete shoulder or curb has been commonly used in order to provide a retaining wall to hold the resurfacing materials in position.

I propose to replace these expensive concrete curbs in connection with such resurfacing jobs by using relatively narrow metal bands or strips or other suitable material placed in an upright position along opposite sides or edges of the old road structure and running parallel with it, with the opposite plates held together with the

tie rods in a manner causing the lower edge of such metal retaining curbs to clamp against the massive outer edge of the old road structure or pavement, and permitting the upper portion of 5 such retaining curb members to extend up above the surface of the old road structure far enough to provide a flanking plate or retaining curb for holding the new resurfacing materials placed upon the old road structure. In this manner a 10 satisfactory curb may be obtained at a very great saving. It can also be very easily and quickly installed, since it eliminates the necessity for the usual curb excavations, the building of forms, the 15 pouring of concrete, and the necessary delay incident to the curing and setting of the concrete, and is satisfactorily anchored against the massive road foundation afforded by the old road structure which affords the base upon which the new surface is laid.

20 A curb such as I provide could be installed with a minimum interruption of traffic and without the necessity of relaying the foundations of the road and without the use of expensive equipment or masonry such as is commonly used in concrete construction work of this character.

The tie rods connecting my metal retaining curb plates may be of various shapes and dimensions, or wire could be used in such a manner that the tie rods would rest on the surface of 30 the old road structure and be covered over by the resurfacing materials used.

It is obvious that when laid in such a manner and when the resurfacing material is in place it would form a very strong structure, and any 35 expansive movements, whether in the resurfacing materials or in the old structure, would tend to exert a pressure against the opposite body, thereby limiting such expansive movement and providing a very strong construction of road.

40 It is the usual practice when resurfacing old road structures with the block type of material such as paving brick or wood blocks and the like to use a cushioning course over the base, such as sand, mastic sand composition, crushed limestone 45 or the like, for the purpose of evening up any depressions which might exist in the old road structure; and for this reason the tie rods above mentioned may be embedded in and covered by such cushioning course. Thus the tie rods would 50 never cause any unevenness or ridges in the surface of the finished pavement. In the event of using asphalt or bituminous surface coverings, it is not necessary that these tie rods should rest on the surface of the old road structure, but they 55 may be spaced therefrom so as to run through and be embedded in the general body of the composition used.

In the drawing, Fig. 1 discloses rectangle side plates 1 and 2 of the simplest design shown connected by a tie rod 3 lying across the top of the surface of the worn road slab 4 with a cushion 5 of mastic sand supporting a layer of resurfacing brick 6.

60 For the sake of illustration of the merits of my invention I show in Figures 1, 2, 3, 4, 5, 6, 7 and 8, a failing concrete road slab or pavement 4 showing signs of disintegration. In Figures 1, 2, 3, 5, 6 and 7 I show a brick resurfacing material 6 over the old road structure. In Figures 1, 2, 3, 4 and 5 I show tie rods 3 of similar construction.

In Figure 5 I have shown side plates 18 and 19 which are overlapped by clips 20 having inturned lower edges 21 which extend below the plates and abut against the massive walls of the old road 75 structure, and in this case the tie rods 3 extend

through both the side plates and the associated clips.

In Figures 7 and 8 there is shown a type of tie rod rectangular in cross section with notches 26 and 27 cut in the opposite edges so as to engage the retaining curb plate 1 as it lies flat across the old road slab after being turned edgewise to be slipped through slots 28 in the curb member 1.

In Figures 8 and 9, the overlapping curb plates 1 are connected by an expansion joint 29 wherein the offset overlying the plates is provided with a slot, and the other offset is provided with a pair of spaced bolts 30 and 31 extending therethrough and provided with detachable threaded nuts 32 and 33. The two bolts are used to hold the retaining curb plates substantially in longitudinal alignment.

In Figure 7 I show a retaining curb plate 34 with a top flange 35 turned in.

It will be noted that in order to strengthen by 20 retaining curb plates it is possible to roll ribs into them for reinforcements or to shape them in other forms in order to add strength.

The aligned retaining curb plates along the road structure may be joined together by bolting, riveting, welding or the like, and at suitable intervals provided with expansion joint connections for taking care of movements due to expansion and contraction. All such curb plates are preferably treated to resist rust by galvanizing or otherwise 30 coating them as well as the tie rods, bolts, rivets and the like.

The tie rods may be fastened by being threaded on the ends and secured by nuts or by being riveted to the plates, or by the slotted locking arrangement illustrated in Fig. 8, or by welding.

The present invention is of value in that it utilizes the old road structure as the basis or foundation for the new surface, and this is possible by reason of the fact that the old road, although more or less impaired on its surface, constitutes a massive closely integrated foundation for the new surfacing materials. Although the old road structure may be rough and uneven in spots, and more or less cracked or disrupted, it nevertheless furnishes a substantially continuous massive foundation presenting vertical side edges against which the metallic side plates can secure an adequate bearing to resist lateral thrusts imposed upon the new surface. This is possible by reason of the fact that the tie rods engage the side plates near the center thereof, so that an outward thrust against the upper edges of the plate will be resisted by the contact of the lower edges against the massive side walls of the old road structure. The invention is directed to a combination in which the old road constitutes the foundation and in which the side plates are anchored in such a way as to prevent lateral displacement, thereby utilizing in full the structural values in the old road and at the same time securing the benefit of an increased road depth and smooth surface without waste of material or labor.

I claim:

1. In an invention of the class described, the combination of an old road structure of integrally massed hard materials presenting substantially vertical side edges and a top surface presenting irregularities in contour due to disintegration of the surface, longitudinally extending vertically standing rigid side plates on each side of the old road structure presenting their lower margins in flatwise contact and close abutment with the side edges of the old road

65

structure, said plates extending upwardly above the old road structure, a newly laid smooth surfaced layer of road surfacing materials overlying the old road structure and filling in the inequalities in the surface thereof and confined between the upstanding side plates and constituting a new road surface, and means for anchoring the side plates against lateral displacement under pressure.

2. In an invention of the class described, the combination of an old road structure of integrally massed hard materials presenting substantially vertical side edges and a top surface presenting irregularities in contour due to disintegration of the surface, longitudinally extending vertically standing rigid side plates on each side of the old road structure presenting their lower margins in flatwise contact and close abutment with the side edges of the old road structure, said plates extending upwardly above the old road structure, a newly laid smooth surfaced layer of road surfacing materials overlying the old road structure and confined between the upstanding side plates and constituting a new road surface filling in the inequalities in the surface of the old road structure, and anchoring rods secured to the side plates intermediate their upper and lower edges and extending inwardly and across the surface of the old road structure for anchoring the side plates at an intermediate point to afford resistance against lateral spreading of the surfacing mate-

rial by abutment of the lower margins of the side plates against the sides of the old road structure.

3. In an invention of the class described, the combination of an old road structure of integrally massed hard materials presenting substantially vertical side edges and a top surface presenting irregularities in contour due to disintegration of the surface, longitudinally extending vertically standing rigid side plates on each side of the old road structure presenting their lower margins in flatwise contact and close abutment with the side edges of the old road structure, said plates extending upwardly above the old road structure, a newly laid smooth surfaced layer of road surfacing materials overlying the old road structure and confined between the upstanding side plates and constituting a new road surface filling in the inequalities in the surface of the old road structure, and tie rods having their ends secured respectively to the side plates intermediate the upper and lower edges thereof and extending across the old road structure closely to the surface thereof and underneath the surface of the new surfacing materials for anchoring the side plates at an intermediate point to afford resistance against lateral spreading of the surfacing material by abutment of the lower margins of the side plates against the sides of the old road structure.
